US00D826731S

(12) United States Design Patent (10) Patent No.: US D826,731 S
O'Neill (45) Date of Patent: * Aug. 28, 2018

(54) PACKAGING

- (71) Applicant: SUGARFINA, INC., Inglewood, CA (US)
(72) Inventor: Rosie Colleen O'Neill, Inglewood, CA (US)
(73) Assignee: SUGARFINA, INC., El Segundo, CA (US)
() Term: 15 Years
(21) Appl. No.: 29/557,383
(22) Filed: Mar. 8, 2016

Related U.S. Application Data

- (63) Continuation of application No. 29/499,564, filed on Aug. 15, 2014, now Pat. No. Des. 755,641.

CLAIM

The ornamental design for a packaging, as shown and described.

DESCRIPTION

FIG. 1 is an exploded perspective view of a packaging showing my new design;

FIG. 2 is a perspective view thereof, shown without the insert and packaging tray for clarity of illustration;

FIG. 3 is a front view thereof;

FIG. 4 is a rear view thereof;

FIG. 5 is top view thereof; and,

FIG. 6 is a side view thereof.

The broken lines shown represent unclaimed subject matter and form no part of the claimed design. The shade lines shown represent surface shading and not surface ornamentation.

1 Claim, 4 Drawing Sheets
